FULL LENGTH CORNER CABINET

Jeremiah L. Campbell, Box 765, Covington, Va.

Filed Dec. 10, 1958, Ser. No. 53,728

Term of patent 14 years

(Cl. D33—19)

FIG. 2 is a rear elevational view of the back of the full length corner cabinet shown in FIG. 1.

FIG. 3 is a top plan view of the full length corner cabinet shown in FIG. 1.

The dominant features of my design reside in those portions shown in full lines of the drawing.

I claim:

The ornamental design for full length corner cabinet, as shown and described.
